UNITED STATES PATENT OFFICE.

AUGUSTUS A. CARTER, OF FAYETTE, IOWA.

REVOLVING DISPLAY-CASE.

1,243,706.

Specification of Letters Patent. Patented Oct. 23, 1917.

Application filed March 2, 1916. Serial No. 81,715.

To all whom it may concern:

Be it known that I, AUGUSTUS A. CARTER, a citizen of the United States, residing at Fayette, in the county of Fayette and State of Iowa, have invented certain new and useful Improvements in Revolving Display-Cases; and I do declare the following to be a full, clear, and exact description of the invention, such as will enable others skilled 10 in the art to which it appertains to make and use the same.

My invention relates to improvements in display cases of the revolving type having a plurality of vertical rows of shelves to support the articles to be displayed, the main object of the invention being to provide guards for holding the articles on the shelves, and to provide means whereby the case may be locked against rotation when 20 any guard is disposed to inoperative position, thus preventing the goods on the shelves from being accidentally thrown therefrom.

With this general object in view, the invention resides in certain novel features of construction, and in unique combinations of parts to be hereinafter fully described and claimed, the descriptive matter being supplemented by the accompanying drawings 30 which constitute a part of this application and in which:

Figure 1 is a side elevation of the improved display case;

Fig. 2 is an enlarged elevation of a portion 35 thereof with the guards open;

Fig. 3 is a horizontal sectional view taken on the plane of the line 3—3 of Fig. 2, showing some of the guards open and others closed; and,

Fig. 4 is an enlarged vertical section 40 through the lower end of the device.

In specifically describing the construction shown in the drawings above briefly described, similar characters will be placed 45 on corresponding parts throughout the several views and reference will be herein made to the numerous elements by their respective indices. To this end, the numeral 1 designates a horizontal base shown in the present embodiment of the invention as of circular 50 contour being provided with a pit 2 in its upper side. Rising from the center of the base 1 is an upright shaft 3 preferably having a laterally extending flange 4 at its 55 lower end which is secured rigidly to said base. A cap 5 carried by the center of a

circular top 6 is rotatably mounted on the upper end of the shaft 3, while a bottom 7 is mounted to rotate on the lower end of said shaft, this bottom being received in the 60 pit 2, and having its upper face disposed flush with the upper side of the base 1.

Extending between and secured rigidly at their ends to the top 6 and bottom 7, is a plurality of upright standards 8 which 65 are spaced circumferentially around a predetermined arc, said standards carrying shelves 9 which are adjustable vertically thereon, these shelves and standards being of any preferred construction. Also extending between the top and the bottom of the case and secured thereto in any desirable way, is a plurality of upright rods 10, said rods being positioned in pairs adjacent the vertical rows of shelves 9 with the rods of 70 each pair disposed adjacent the opposite sides of said shelves to prevent articles A resting thereon from falling laterally therefrom.

For the purpose of further holding the 80 articles A upon the shelves 9, pairs of laterally swinging guards 11 are provided, said pairs being disposed one adjacent each vertical row of shelves. Each guard 11 is in the form of an upright wire or the like having 85 its upper end disposed contiguous to the top 6 and bent laterally, said ends being formed with pivot eyes 12 which surround the rods 10. The lower ends of the guards 11 are bent laterally and coiled at 13 to form additional pivot eyes receiving the lower ends 90 of the rods 10, the wire after forming these eyes 13, being extended laterally in horizontal directions to form crank arms 14.

The arms 14 are shown in the present embodiment of the invention as projecting through apertures 15 in the vertical sides 16 of channel shaped slides 17, one of these slides being disposed between the guards of each pair. Each slide 17 is formed in its 100 lower side with one or more longitudinal slots 18 receiving screws or the like 19 which are driven therethrough into the bottom 7, said slides thus having a predetermined amount of radial movement which will allow 105 them to move the guards 11 to operative position when forced inwardly, and to inoperative position when pulled outwardly as shown clearly in the drawings.

In order that the articles A may not be 110 accidentally thrown from the shelves 9 by rotation of the case when certain guards 11

stand in open position, it is highly desirable to provide some simple means whereby the case may be locked against rotation when any of the slides are so positioned as to open the guards. It is also essential to devise some efficient means for locking the slides in the position in which they hold the guards closed. In accomplishing these results, the slides in question are equipped with vertically movable locking pins 20 shown as carried by the outer ends of appropriate springs 21 secured to said slides. When the latter are moved inwardly to close the guards, the pins 20 are received in sockets 22 in the bottom 7 to hold said slides in this position, but when said slides are moved outwardly to open the guards, the pins 20 are adapted to be received in additional sockets 23 formed in the upper side of the base 1. Thus, the entire case is now held against rotation while the guards are open.

The foregoing defines the preferred form of my invention, but it will be readily understood that numerous changes may be made within the scope of the invention as pointed out in the appended claims without sacrificing the primary advantages thereof. Furthermore, the improved case may be constructed for displaying numerous kinds of articles, although in its present embodiment it is designed primarily for displaying ribbons.

I claim:

1. A revolving display case comprising a plurality of shelves adapted to support the articles to be displayed, movable guards for holding such articles on the shelves, and means for locking the case against rotation when a guard is moved to inoperative position.

2. A revolving display case comprising a plurality of vertical rows of shelves adapted to support the articles to be displayed, movable guards for holding such articles on the shelves, movable operating members for disposing said guards to and holding them respectively in operative and inoperative positions, and means for locking the case against revolution when an operating member is moved to dispose its guard to inoperative position.

3. A revolving display case comprising a plurality of vertical rows of shelves adapted to support the articles to be displayed, movable guards for holding said articles on the shelves, movable operating members for moving said guards to operative and inoperative positions, latches on said operating members for holding them in position to retain their respective guards in operative relation with the shelves, and a fixed locking member with which said latches coöperate to lock the case against revolution when an operating member is so disposed as to release its respective guard.

4. A revolving display case comprising a plurality of vertical rows of shelves to support the articles to be displayed, upright laterally swinging guards adjacent said rows of shelves to hold the articles thereon, crank arms extending laterally from said guards, slideable operating members to which said arms are connected, for operating the guards, latches carried by said operating members for holding the same in position to retain their respective guards in operative relation with the shelves, and a fixed locking member with which said latches coöperate when the operating members are moved to another position, thereby locking the case against rotation.

5. A revolving display case comprising a plurality of vertical rows of shelves to support the articles to be displayed, upright rods disposed at the opposite sides of said shelves for preventing said articles from falling laterally therefrom, upright laterally swinging guards adjacent the front ends of said shelves to coöperate with said rods in holding the articles thereon, said guards having upper and lower outwardly extending arms pivotally mounted on said rods, crank arms extending laterally from the lower ends of the guards, movable operating members with which said crank arms are connected for operating the guards, latches carried by said members for locking them in position to retain their respective guards in operative relation with the shelves, and a fixed locking member with which said latches coöperate when the operating members are so moved as to release the guards, thereby locking the case against rotation.

6. A display case comprising a base having in its top a pit and having an arcuate series of sockets surrounding said pit and opening through its top, an upright shaft rising from the center of the pit, a top and a bottom member rotatably mounted respectively on the upper and lower ends of said shaft, said bottom member being disposed in the pit, vertical rows of shelves between the top and bottom members, vertical rods extending between said members and disposed on opposite sides of said shelves to prevent articles thereon from falling laterally therefrom, upright swinging guards adjacent the front ends of said shelves and coöoperating with the aforesaid rods to hold the articles thereon, said guards having laterally extending arms on their upper and lower ends pivotally mounted on the upper and lower ends of said rods, crank arms extending laterally from the lower ends of said guards, slides mounted on the bottom member and having connection with said crank arms for operating the guards, said slides being movable inwardly to close said guards and outwardly to open the same, and latches carried

by the slides for normally locking the same against outward movement, said latches being adapted for reception in the aforesaid sockets when the slides are moved outwardly 5 thereby locking the case against rotation.

7. A display case comprising a vertical row of shelves adapted to support the articles to be displayed, vertical rods disposed adjacent the opposite sides of said 10 shelves to prevent the articles thereon from falling laterally therefrom, upright guards adjacent the front end of said shelves and coöperating with said rods in retaining the articles thereon, said guards having laterally extending arms at their upper and lower ends pivotally mounted on the aforesaid rods, crank arms extending laterally from the lower ends of said guards, a movable operating member with which said 15 crank arms are connected in a pivotal manner, and a latch for holding said operating member in position to retain the guards in operative relation with the shelves.

8. A display case comprising a vertical

row of shelves, a pair of laterally swinging 25 vertical guards on opposite sides of said row and extending approximately throughout the length thereof for holding articles on the shelves, and means for locking said guards in operative relation to the shelves.

9. A display case comprising a vertical 30 row of shelves, a pair of laterally swinging vertical guards on opposite sides of said row and extending approximately throughout the length thereof for holding articles on the shelves, an operating member connected with said guards for simultaneously moving the two and means for locking said member in position to retain said guards in operative relation with the shelves.

In testimony whereof I have hereunto set my hand in presence of two subscribing witnesses.

AUGUSTUS A. CARTER.
